UNITED STATES PATENT OFFICE

AXEL OLOF ENGBERG AND FREDRIK CARLSTEDT, OF STOCKHOLM, SWEDEN, AS-SIGNORS TO INVENTIA PATENT-VERWERTUNGS-GESELLSCHAFT, OF SCHAFF-HAUSEN, SWITZERLAND, A CORPORATION OF SWITZERLAND

COUPLING FOR CLEANERS

Original application filed June 15, 1926, Serial No. 116,123, and in Sweden December 16, 1925. Divided and this application filed December 22, 1926. Serial No. 156,464.

This application is a division of our co-pending application Serial No. 116,123, filed June 15th, 1926.

Our invention relates to cleaners of the type wherein a current of air is employed. More particularly, our invention relates to cleaners of the type generally known as vacuum cleaners. Our cleaner is, however, not alone a vacuum cleaner, that is, one which induces the air containing the dust and dirt, but is also a blower by means of which a forced current of air can be projected against a place to be cleaned.

One object of our invention is to produce a cleaner which is readily converted from a vacuum cleaner to a suitable blower. To accomplish this, we provide a coupling which is readily insertable in either of several openings and which is adapted to receive a hose. The coupling is of such construction as to provide air passages of variable size. It also is so constructed as to provide a neat appearance when fitted to the cleaner unit. A further object is to provide a novel coupling between the hose member and main unit of a vacuum cleaner.

Referring to the accompanying drawing which shows a preferred form of apparatus embodying the invention:

Fig. 1 is a longitudinal cross-sectional view of a cleaner embodying the invention; and

Fig. 2 is an assembly view of a cleaner comprising the main unit shown in Fig. 1.

The main unit of the cleaner comprises a casing, in turn comprising a main cylindrical barrel 10 consisting of stiff material such as thin sheet metal surrounded by fibrous material or leather composition and having attached thereto at one end a metal bell 11, and, at the other end, a metal housing 12. Housing 12 contains the electric motor 13 and the fan 14 which serve to cause flow of air through the casing in the direction indicated by arrows. Forward of housing 12, that is, in direction toward bell 11, is a disinfecting air filter 15 and forward of the filter 15 is a dust bag 16. The forward end of the dust bag consists of a flanged metal ring 17, around the flange of which is placed a rubber washer 18. The flange of ring 17 and the rubber

washer 18 are clamped between bell 11 and the flange 19 of a circular ring 20 attached to the forward end of the main barrel by means of rivets 21 and forming part of the main barrel.

A central coupling 23 is screw-threaded into a central opening 8 in bell 11 by means of threads 24 and has a central tapered passageway into which, in normal operation, the tapered end of a flexible metal air hose 26 is jammed. The coupling comprises a ring portion 31, a central cylindrical portion 32 of smaller diameter than the ring portion and coaxial with the ring portion and an annular bridge section 33 connecting the ring portion with the central portion and extending obliquely to the axis of the ring portion and the central portion. The central tapered bore 25 extending through the central portion has its smallest width adjacent the ring portion. The central cylindrical portion extends axially a substantial distance from the narrow part of the bridge section to provide a hand grip surface. The hand grip surface is a roughened surface due to ribs 27, thus providing an easy grasp. Coupling 23 is readily removable from bell 11 by mere application of and turning by the hand.

Air hose 26 leads to mouth piece 22 into which the dust passes in suction operation, an extension 9 being used between the mouth piece and the air hose, if desired.

In normal operation air containing dust passes in through passageway 25 from tube 26 and mouth piece 22 and into dust bag 16 where the dust is deposited, and from which the air, after passing through the cloth of the dust bag, passes through the filter 15, thence through fan 14 and out to the atmosphere through opening 28 at the rear end of housing 12. Opening 8 may be considered as the air inlet and opening 28 as the air outlet for the unit.

The dust bag of which the main portion is preferably made of cloth, is attached to ring 17 in any desired manner. The dust bag can be removed from the barrel, to expel the dust collected within the same, by first unclamping and removing bell 11, after which the dust bag is drawn forward through the for-

ward end opening of the barrel formed by ring 20. As preferred means for clamping bell 11 to the main barrel there are used a series of spring clamps 29 which comprise a lever 30, a hook 37 and a spring 36. Bell 11 is unclamped by pulling lever 30 away from the barrel, whereby the spring 36 is released and the hook 37 can be removed from the shoulder 35 on bell 11.

10 The central coupling 23 serves two purposes: First, it serves to prevent transmission of electricity from the main parts of the cleaner to the hose 26 and thus to the body of the operator, and for this purpose, is made of non-conducting material, preferably 15 ebonite; and second, it serves to make the cleaner reversible and transform the same from a vacuum cleaner into a blower. The reason for making coupling 23 of non-conducting material is that it might happen that 20 parts become short-circuited and this member serves to prevent a shock to the person operating the cleaner. For the second purpose mentioned, namely, to transform a 25 vacuum cleaner into a blower, the rear opening 28 in housing 12 is made of the same size and with the same number of threads per inch as the opening in bell 11 in which coupling 23 is shown as inserted.

30 If it is desired to use the cleaner to blow air, coupling 23 is removed from the opening 8 in bell 11 and screwed into opening 28. Hose 26 may then be fitted into coupling 23 with or without the attachment of a mouth 35 piece. In this operation it is obviously preferable to remove the dust bag. Upon switching on the current, air is then drawn in through the opening 8 in bell 11, through the main barrel, through fan 14, past motor 13 40 and out through opening 28 to form the ventilating or blowing current.

The opening 28 and the corresponding opening 8 in bell 11 are made considerably larger than the opening 25. The purpose 45 of this construction is to reduce the friction and throttling losses. If the opening 8 in bell 11 were as small as opening 25, a considerable resistance would result for the air flowing through the opening 8 when coupling 23 50 is inserted in opening 28 and the apparatus is used as a blower. Also, in normal evacuating operation, it is preferable to have a large air outlet, in order to avoid resistance on the outlet side of the fan and accompanying loss in 55 efficiency.

The main barrel 10 and associated parts are mounted upon runners 60 of which there are two, one positioned on either side of the main barrel, and which form a sled carriage 60 for the main unit.

In order to carry the main cleaner unit comprising a main barrel 10 and attached parts, a resilient strap 65 is provided.

Having thus described our invention, what 65 we claim is:

A coupling for use in vacuum cleaners comprising a ring portion, a central cylindrical portion of smaller diameter than the ring portion coaxial with the ring portion and an annular bridge section connecting the ring portion with the central portion and extending obliquely to the axis of the ring portion and the central portion, said central portion having a passageway therethrough, and said central cylindrical portion extending axially a substantial distance from the narrow part of the bridge section and providing a hand grip surface.

Signed at Stockholm, Sweden, this 17th day of November, A. D. 1926.

AXEL OLAF ENGBERG. 80
FREDRIK CARLSTEDT.
